UNITED STATES PATENT OFFICE.

JOSEF IVAN STAMPAHAR AND JOSEPH FRANK ROM, OF RED LODGE, MONTANA.

SPARK-ARRESTER.

1,030,028.

Specification of Letters Patent. Patented June 18, 1912.

Application filed August 25, 1911. Serial No. 645,960.

To all whom it may concern:

Be it known that we, JOSEF IVAN STAMPAHAR and JOSEPH FRANK ROM, citizens of the United States, residing at Red Lodge, in the county of Carbon, State of Montana, have invented certain new and useful Improvements in Spark-Arresters; and we do hereby declare the following to be a full, clear, and exact description of the invention, such as will enable others skilled in the art to which it appertains to make and use the same.

This invention relates to an improvement in spark arresters adapted for connection to locomotive smoke stacks for preventing sparks and cinders from being ejected therefrom.

The principal object of this invention is to provide an arrester for the purpose described which is composed of a minimum number of parts, is therefore simple in construction, and is cheap to manufacture.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction within the scope of the claims, may be resorted to without departing from the spirit or sacrificing any of the advantages of the invention.

In the drawing: Figure 1 is a side elevation of a locomotive smoke stack showing our invention applied thereto, Fig. 2 is a vertical sectional view through the same, Fig. 3 is a horizontal sectional view taken on the line 3—3 of Fig. 2.

Like reference numerals designate corresponding parts in all the figures of the drawing.

Referring to the drawing, the invention comprises a smoke stack 5 to the upper end of which is attached our improved spark arrester, which includes a cylindrical casing 6. This casing has a reduced lower end 7 adapted to be disposed around the upper end of the stack 5. The casing above the reduced portion 7 flares outwardly, as indicated by the reference numeral 8, and thence upwardly to form a wall 9, the diameter of the outer portion of the casing being considerably greater than the diameter of the smoke stack 5. This casing is secured

to the stack by means of bolts 10 or other suitable fastening means, which are passed through suitable openings respectively formed in the reduced portion 7 and the stack 5.

Disposed within the casing 6 and resting upon the flared portion 8 thereof is the upper end of an inverted cone 11. This cone is secured in position by means of bolts 12 or other suitable fastening means, and the apex 13 of said cone projects downwardly into the stack 5 below the upper end thereof. Secured to the inner faces of the wall 9 of the casing and near the upper end thereof are spaced brackets 14, and upon these brackets is seated a rim 15 of a horizontal screen 16, said rim and bracket being securely held together by means of bolts 17. Transverse bolts 18 are employed for securing the brackets 14 to the wall 9 of the casing, and these bolts furthermore are employed for retaining the rim 19 of a convexed screen 20 to said casing, the last mentioned screen projecting above the upper end of the casing 6.

Secured by bolts 21 to the inner face of the wall 9 intermediate the screen 11 and the screens 16 are spaced brackets 20a. Seated upon these brackets is the rim 22 of a screen 23, said rim and bracket being secured together by bolts 24 or other suitable fastening means.

The screens 11—23—16 and 20 are formed of wire mesh, the mesh of the screens being reduced in the order named.

From the foregoing, it will be observed that any cinders or sparks which pass the lower or cone screen 11 will engage the next screen 23, and should they fail to be retarded by this screen they will engage the screen 16. Should, however, they pass this screen, they will be stopped by the small mesh screen 20 at the top.

What is claimed is:—

1. The combination with a smoke stack, of a spark arrester consisting of a casing having a reduced lower end disposed around and secured to the upper end of the stack, said casing being flared outwardly above the stack and thence upwardly to form a wall, an inverted wire mesh cone resting upon the flared portion of the casing and having its apex disposed centrally within the stack, a plurality of spaced screens of graduating meshes secured within the casing and disposed above the first mentioned screen.

2. The combination with a smoke stack, of a spark arrester consisting of a casing having a reduced lower end disposed around and secured to the upper end of the stack, 5 said casing being flared outwardly above the stack and thence upwardly to form a wall, an inverted wire mesh cone resting upon the flared portion of the casing and having its apex disposed centrally within the stack, and a convexed screen disposed 10 at the upper end of the casing and having a rim disposed around said casing.

3. The combination with a smoke stack, of a spark arrester consisting of a casing 15 having a reduced lower end disposed around and secured to the upper end of the stack, said casing being flared outwardly above the stack and thence upwardly to form a wall, an inverted wire mesh cone resting

upon the flared portion of the casing and 20 having its apex disposed centrally within the stack, a convexed screen disposed at the upper end of the casing and having a rim disposed around said casing, brackets disposed within the casing between said 25 screens, bolts respectively connecting the brackets, casing and rim of the first mentioned screen for securing said parts together, and a screen supported upon said brackets. 30

In testimony whereof we affix our signatures in presence of two witnesses.

JOSEF IVAN STAMPAHAR.
JOSEPH FRANK ROM.
